UNITED STATES PATENT OFFICE.

GUY L. HAMMOND AND WILLIAM NICHOLAS, OF BRIDGEPORT, CONNECTICUT, ASSIGNORS TO THE BLACK ROCK MFG. CO., OF BRIDGEPORT, CONNECTICUT, A CORPORATION OF CONNECTICUT.

CALENDERING MACHINE.

Application filed July 6, 1922. Serial No. 573,218.

To all whom it may concern:

Be it known that GUY L. HAMMOND and WILLIAM NICHOLAS, a citizen of the United States and a subject of the King of Great Britain, respectively, and residents of Bridgeport, in the county of Fairfield and State of Connecticut, have invented certain new and useful Improvements in Calendering Machines, of which the following is a specification.

This invention relates to improvements in calendering machines, and particularly machines of this character for shaping, forming and calendering material such as rubber composition, asbestos and the like, into strips, bars or sheets, for instance, like that employed on brake linings or sheet packing, asbestos or the like.

An object is to provide a machine in which the material may be shaped or finished with a high degree of accuracy, as to dimensions and uniformity, and in which the density and surface desired may be maintained or regulated to any desired standard.

A further object is to provide a calibrated gauge, by which the accuracy of the calendering may be adjusted and maintained within the closest limits, and to permit of the adjustment of such means as desired, to accommodate and calender sheets and strips of varying thicknesses and widths.

Another object is to enable the adjustment and setting of the machine so as to insure the reliable production of materials of definite and standard dimensions and uniform quality, further to provide any desired degree of compression upon the stock by the calendering rolls and particularly to adjustably position the several rolls in cooperating relation, to the end that the strip produced will have both perfect edges and side faces.

Other objects are simplicity, freedom from parts liable to get out of order and the easy removal and replacement of wearing elements.

With the above and other objects in view, an embodiment of the invention is shown in the accompanying drawings, and this embodiment will be hereinafter more fully described with reference thereto, and finally pointed out in the claims.

In the drawings:

Fig. 1 is a front elevation of a calendering machine embodying the invention;

Fig. 2 is an end view thereof;

Fig. 3 is a fragmentary detail view, partially in front elevation and partially in vertical section of the upper calendering roll, and the mounting, driving and adjustment means therefor; and

Fig. 4 is a horizontal sectional view along the line 4—4 of Fig. 1.

Similar reference characters indicate corresponding parts throughout the several figures of the drawings.

The machine, according to the present embodiment of the invention, comprises a rectangular bed-plate 10, supported upon end standards 11 and mounting a pair of vertically-disposed bearing frames 12 and 13, braced and connected at their upper ends by a tie-beam or brace 14.

An electric driving motor 15 is mounted upon a support 16 that may be secured to the end standards and in spaced relation to the floor. The driving shaft 17 has a bearing in the end of a housing 18, bolted to the standard 11 at one end, the shaft being provided within the housing with a bevel pinion 19, meshing with a bevel gear 20, mounted upon a vertical shaft 21. The shaft 21 has a flanged thrust-bearing adjacent its reduced end 22 that is journaled in the base 85 of the housing, the bore of the bearing being bushed, as at 23. This shaft is also journaled in a bushed bearing portion 24 in the top of the housing and includes a collar 21' that is positioned against the housing and forms a thrust bearing against any lifting tendency of the gear 20 and its shaft. The housing is of the two-piece separable type, to permit access to the gears when desired.

The upper end portion of the shaft 21 is connected by a coupling 37 with a worm shaft 37' which is provided with a pair of spaced right and left worms 25 and 26 (Fig. 2). The worm 25 is enclosed in a cylindrical housing 27, having an integral gear enclosing extension 28, and also provided with integral plate portions 29 and 30 bolted to the frame 12. A removable cover plate 31 is mounted upon the outer side of the extension 28; and at its inner side, there is provided a bearing portion 32, in which is journaled one end of a horizontally-disposed shaft 33, provided within the housing with

a worm gear 34, meshing with the lower worm 25. The other end of the shaft 33 is journaled in a bearing portion 35 of the frame 13, and adjacent said frame, and between it and the frame 13, there is mounted thereon an adjustable lower calender roll 36, which together with the shaft is fixed against vertical movement. One part of the coupling 37 is bolted to the lower shaft 21 and the upper part is similarly secured to the lower end of the worm shaft 37 so as to detachably and operatively connect the two shafts.

A tubular post 27^a having a flanged lower end portion is secured to the lower end of the housing 27 by means of screws 27^b, and extends through and above said housing to form a guide upon which a second cylindrical housing 38 is slidably mounted. This post also serves as a bearing and inclosure for the worm shaft 37^a and worms 25 and 26. A gear-enclosing extension 39 is formed upon one side of the housing 38, being enclosed at its outer side by a removable cover-plate 40. A slide-block 41 forming an adjustable bearing is secured to the inner side of the extension 39 by screws 42, and is vertically movable in a slideway 43 provided in the frame 12. Guide flanges 45 and 46 are formed upon the slide block, which engage the forward edges of the slide-way, while removable guide plates 47 and 48 are secured to the inner side of the block 49, and engage the inner edges of the slideway.

35 A calender roll shaft 50 is journaled at one end in the slide-block 41, being provided at its projecting reduced extremity 51 with a worm gear 52, that meshes with and is driven by the worm 26. The other end of the shaft 50 is journaled in a slide-block 53, guided to have vertical movement in a slide-way 54 of the frame 13.

An upper vertically adjustable calender roll 56 is adjustably mounted upon the shaft 50, in superimposed and adjustably spaced relation to the roll 36 positioned therebeneath. Both the rolls 36 and 56 are adjustable lengthwise upon their respective shafts by means of the shafts being threaded as at 44, and provided with nuts 55 which are threadably mounted upon the portions 44 of the shaft and are set against the sides of the rolls. These rolls are driven to cooperate as surfacing and compressing rolls, their spacing being adjustable through raising or lowering the upper roll 56, by means presently to be described.

60 An edge-forming calendering roll 57 spans the space between the rolls 36 and 56, engaging the side surfaces thereof, and is mounted upon a vertical shaft 58, supported in laterally disposed brackets 59 and 60 secured to the frame 12. A bevel gear 61 is mounted upon the lower end of the shaft 58, and meshes with a bevel drive gear 62,

secured upon the lower roll shaft 33, to drive the roll 57 at a surface speed corresponding to the surface speed of the rolls 36 and 56.

The upper calender roll 56 is adjustable vertically, by means of a pair of lifting screws 63 and 64, threaded to engage the body of the gears 71 and 72 mounted in the frames 12 and 13 respectively. The lower ends of these two screws are secured to the slide-blocks 41 and 53 by means of screws 65, and adapted to move together with the upper calender roll 56, the worm gear 52 and the housings 38—39, the gear 52 turning upon the worm 26 during such movement. These gears mesh with and are driven by bevel gears 76 and 77 mounted upon a horizontal shaft 73 rotatably mounted in bearing brackets 74 and 75, above the brace beam 14. This shaft 73 is provided at its outer end with a removable crank 78 adapted for manual turning of the shaft, which operation through the bevel gear and screw connections raises or lowers the calender roll 56, depending upon the operation of turning.

90 The shaft 73 has mounted thereon a disk 79 and is provided at its periphery with calibrations over which a fixed index 80, mounted upon the brace-beam 14, is disposed to indicate the degree of turning of the shaft, and thereby, the relative spacing of the calender rolls and consequent thickness of product when rolled.

95 A support 81 is mounted upon the frame 13 and a standard 82, being provided along its upper surface with a longitudinal slotted slide-way 83, in which a slide 84 is disposed and retained by means of removable retaining strips 85 and 86. A feed screw 87 is secured to the head and extends through a longitudinally fixed nut 88, rotatably mounted in a bearing 89 of the support 81, a graduated crank-wheel 90 being fixed to the nut to permit its manual turning. A pointer 67 is secured to the slide and is disposed toward the crank wheel in position to be read in connection with the graduations upon the wheel 90 to determine the proper adjustment for certain widths of strips to be rolled.

100 A plate 91 is secured to the head 84 and extends in spaced relation above the projecting base portion of the slide and forming with said portion a support for the interchangeable horizontal roll A that is removably positioned in the recess 92, the inner operative edge portion of said roll operating between the before mentioned calendering rolls 36 and 56 and in adjustable spaced relation to the fixed roll 57 as shown 110 in Fig. 4. The roll A is provided with a hub portion 94 through which a removable pin 93 is positioned to form a bearing upon which rolls A of different size and thickness are removably supported to calendar strips 115 120 125 130

of brake lining and other material of different thickness and widths, the pin 93 being held in position by means of a set screw 95, as shown in Fig. 1.

5. The roll A is interchangeable with similar rolls of different thicknesses and as the degree of its insertion between the rolls 36 and 56, permits of the production of any desired width of strip or sheet it is possible 10 by changing this one element of the machine to produce strips or sheets of any desired thickness.

In operation, the strip or sheet of material which may be of any suitable compressible material, as rubber composition, asbestos, or the like, is continuously fed through the pass, formed by the upper and lower rolls 36 and 56, and the edging rolls 57 and A, thereby compressing and forming it.

The product of the machine is uniform, as to finish and density, and its upper and lower surfaces and edges are calendered to an exact standard or uniformity. The formation of burs, fins, or other irregularities is entirely prevented. The parts are such that they will not readily get out of order, they may be easily dismounted and replaced and their adjustment may be brought about with the greatest precision.

I have illustrated and described a preferred and satisfactory embodiment of the invention, but it is obvious that changes may be made therein within the spirit and scope thereof, as defined in the appended claims:

1. In a machine of the character described, a pair of spaced calendering or forming rolls, adapted to receive a strip of work between them, and an edge calendering or forming roll having its periphery spanning the space between the first rolls, and engaging the side surfaces thereof, and a second edge forming roll having its edge disposed between the peripheries of the pair of spaced rolls and adjustable between them and toward and from the first edge forming roll.

2. In a machine of the character described, a pair of spaced calendering or forming rolls, adapted to receive a work-piece between them, means adapted to simultaneously and equally rotate said rolls in opposite directions, an edge calendering or forming roll spanning the space between said first rolls and engaging the side surfaces thereof, and means for driving said edge forming roll at a surface speed corresponding to the surface speed of said first rolls.

3. In a machine of the character described, a pair of spaced calendering or forming rolls, adapted to receive a work-piece between them, means adapted to simultaneously and equally rotate said rolls

in opposite directions, an edge calendering or forming roll spanning the space between said first rolls, and gearing between said edge forming roll and one of said first rolls for driving said edge forming roll at a surface speed corresponding to the surface speed of said first rolls.

4. In a machine of the character described, a pair of calendering or forming rolls adapted to receive a work-piece between them, edge-forming means having its surface extending above and below the peripheries of said rolls and engaging the side surfaces thereof, means for adjusting one of said rolls relatively to the other to vary their spacing, and means driving said edge forming means at a surface speed equal to the surface speeds of the forming rolls.

5. In a machine of the character described a pair of spaced calendering or forming elements including a roll, adapted to receive a work-piece between them, one of said elements being fixed against bodily transverse movement, edge-forming means having its surface extending between the peripheries of the elements, and means for moving said non-fixed first element toward or away from said fixed element, and means interchangeably mounting the edge forming means and providing for its adjustment between the rolls.

6. In a machine of the character described, a pair of spaced calendering or forming rolls, adapted to receive a work-piece between them, parallel shafts supporting said rolls, spiral gears upon said shafts, a drive shaft at right angles to said parallel shafts, and right and left worms upon said drive shaft meshing with said spiral gears, an edge calendering roll spanning the space between the said first rolls and engaging the side surfaces thereof, and gearing between said edge calendering roll and one of said first rolls for driving said edge calendering roll at a surface speed corresponding to the surface speeds of said first rolls.

7. In a machine of the character described, a pair of spaced calendering or forming rolls, adapted to receive a work-piece between them, parallel shafts supporting said rolls, one of said rolls being adapted to be adjusted toward or away from said other roll, spiral gears upon said shafts, a drive shaft at right angles to said parallel shafts, and right and left worms upon said drive shaft meshing with said spiral gears, one of said gears adapted to roll upon its worm during adjusting movement of the roll connected therewith, an edge calendering roll spanning the space between the said first rolls and engaging the side surfaces thereof, and gearing between said edge calendering roll and one of said first rolls for driving said edge calendering roll at a surface speed corre-

sponding to the surface speeds of said first rolls.

8. In a machine of the character described, a pair of spaced calendering or forming rolls, adapted to receive a work-piece between them, parallel shafts supporting said rolls, one of said rolls being adapted to be adjusted toward or away from said other roll, spiral gears upon said shafts, a drive shaft 10 at right angles to said parallel shafts, right and left worms upon said drive shaft meshing with said spiral gears, one of said gears adapted to roll upon its worm during adjusting movement of the roll connected therewith, and housings for said worms and 15 gears, one of said housings being movable with the adjusting movement of said roll, an edge calendering roll spanning the space between the said first rolls and engaging the side surfaces thereof, and gearing between 20 said edge calendering roll and one of said first rolls for driving said edge calendering roll at a surface speed corresponding to the surface speeds of said first rolls.
9. In a machine of the character described, a pair of spaced calendering or forming elements, adapted to receive a work-piece between them, an edge calendering or forming element having its surface spanning the space between said first elements, edge calendering or forming means rotatably supported between said elements, and means for shifting said last means to vary the space between said elements and said edge forming elements.

10. In a machine of the character described, a plurality of spaced calendering or

forming elements, adapted to receive a work-piece between them, edge calendering or forming means, an adjustable support therefore, and a pair of cooperating separable members carried by said support and adapted to rotatably mount said last means. 40

11. In a machine of the character described, a pair of spaced calendering or forming elements each including a roll, and adapted to receive a work-piece between them, edge forming means at the side of said rolls, means for rotating said elements and with them the rolls, and means for driving the edge forming means from one of said calendering or forming elements. 45

12. In a machine of the character described, a pair of calendering or forming rolls, means for driving said rolls, edge forming means at one side of said rolls, and means for driving the edge forming means at a speed equal to the surface speeds of the rolls. 50

13. In a machine of the character described, a pair of spaced calendering or forming elements each including a roll, means for rotating said elements and with them the rolls, an edge forming means at one side of the rolls, and means to drive the edge forming element from one of said calendering or forming elements and at the same rate of surface speed as that of the rolls. 60

Signed at Bridgeport in the county of 70
Fairfield and State of Connecticut this 24th
day of June, A. D., 1922.

GUY L. HAMMOND.
